UNITED STATES PATENT OFFICE.

EDWARD F. GEHRKENS, OF SCHENECTADY, NEW YORK, ASSIGNOR TO GENERAL ELECTRIC COMPANY, A CORPORATION OF NEW YORK.

VARIABLE-VOLTAGE TRANSFORMER.

No. 890,638.

Specification of Letters Patent.

Patented June 16, 1908.

Application filed July 26, 1906, Serial No. 327,915. Renewed January 31, 1908. Serial No. 413,614.

To all whom it may concern:

Be it known that I, EDWARD F. GEHRKENS, a citizen of the United States, residing at Schenectady, county of Schenectady, State of New York, have invented certain new and useful Improvements in Variable-Voltage Transformers, of which the following is a specification.

My invention relates to variable-voltage transformers of a type proposed heretofore, comprising a magnetic core with primary and secondary coils thereon, with two movable magnetic members,—one arranged to open the magnetic circuit threading both the primary and secondary coils, and the other to close a magnetic circuit outside of the secondary coil. As these transformers have been designed heretofore, it has been necessary to leave a space between the primary and secondary coils for the shunting magnetic member when it is moved into position. This spacing apart of the primary and secondary coils not only makes the structure of the transformer less compact, but produces considerable magnetic leakage, so that even when the magnetic members are in the position of maximum induced voltage not all the primary flux threads the secondary coil. Consequently, the efficiency of the transformer is impaired, and the reactance of the primary circuit is increased by this leakage flux.

The object of my invention is to improve the efficiency of such transformers, and I accomplish this result by so arranging the secondary coil and the movable magnetic members that the primary and secondary coils may be placed close together, thereby reducing magnetic leakage to a minimum.

My invention will best be understood by reference to the accompanying drawings, in which

Figure 1 shows a side elevation in cross-section of a variable-voltage transformer arranged in accordance with my invention; and Fig. 2 shows an end-elevation in cross-section on the lines 2 2 of Fig. 1.

In the drawings, A represents a magnetic core, which is of the well known "shell-type" construction, comprising three parallel members joined at both ends with primary and secondary coils side-by-side on the central member. The primary and secondary coils are indicated by B and C, respectively. This

core A is of the usual construction, except that the portion D of the central member, which is inclosed by the secondary coil C, is movable with respect to the rest of the core, so as to allow the coil C to be moved in its own plane downward out of line with the primary coil. With the two coils in the position shown in the drawings, the member D serves practically to close the magnetic circuit of the core A, so that the transformer operates like an ordinary "shell-type" transformer. This position of the secondary coil is the position of maximum induced voltage. To reduce the secondary voltage, the coil C is lowered out of line with the primary coil, carrying with it the member D. A second member E is placed above the coil C, and, when the coil is lowered, this member is brought into the space vacated by the member D and the coil so as to close the magnetic circuit of the primary coil outside of the coil C. The member E enters the core A before member D leaves it, thereby gradually shunting the primary flux around the secondary coil.

Any suitable means for moving the coil C and members D and E may be employed. I have indicated for this purpose a rope F passing over a pulley G and provided with a suitable counter-weight H.

Any other suitable operating means may be employed. Accordingly, I do not desire to limit myself to the particular construction and arrangement of parts here shown, but aim in the appended claims to cover all modifications which are within the scope of my invention.

What I claim as new, and desire to secure by Letters Patent of the United States, is,

1. In a variable-voltage transformer, a magnetic core, flat primary and secondary coils side-by-side on said core, said secondary coil and the portion of the core inclosed thereby being movable in the plane of the coil away from the primary, and a magnetic member arranged to be moved into the space vacated by said core portion.

2. In a variable-voltage transformer, a magnetic core, flat primary and secondary coils side-by-side on said core, said secondary coil and the portion of the core inclosed thereby being movable in the plane of the coil away from the primary, and a magnetic member carried by the secondary coil adapt-

ed to be brought by the movement of the coil into the space vacated by said core portion.

3. In a variable-voltage transformer, an open magnetic core, a flat primary coil thereon, a flat secondary coil adjacent to the primary and movable in its own plane into and out of line with the primary coil, a magnetic member carried within the secondary 10 coil and adapted to complete the magnetic circuit of the primary coil when the secondary is in line therewith, and a second magnetic member carried outside the secondary coil and adapted to complete the 15 magnetic circuit of the primary coil when the secondary is out of line therewith.

4. In a variable-voltage transformer, a magnetic core, flat primary and secondary coils thereon, said secondary coil and the 20 portion of the core inclosed thereby being movable away from the primary in the plane of the secondary coil, and a magnetic member secured to and movable with the secondary coil adapted to complete a magnetic 25 circuit for the primary coil outside of the secondary coil.

5. In a variable-voltage transformer, a magnetic core, flat primary and secondary coils thereon, the secondary coil and the 30 portion of the core inclosed thereby being movable in the plane of the coil away from the primary, and a magnetic member arranged to be moved into position to close a magnetic circuit for the primary coil out- 35 side of the secondary coil.

6. In a variable-voltage shell-type transformer, a magnetic core substantially rec-

tangular with a substantially rectangular hollow center and a portion of the core projecting into this center, a flat primary coil 40 surrounding the projecting core portion and partially surrounded by the remainder of the core, and a flat secondary coil movable in its own plane in the hollow center and inclosing a magnetic member movable with it, and a 45 second magnetic member for completing the magnetic circuit of the primary coil when the secondary coil is moved out of inductive relation therewith.

7. In a variable-voltage shell-type transformer, a magnetic core substantially rectangular with a substantially rectangular hollow center and a portion of the core projecting into this center, a flat primary coil 50 surrounding the projecting portion of the core and surrounded as to its external faces and sides by the remainder of the core, and a flat secondary coil movable in its own plane within the hollow center and inclosing a magnetic member movable with it and 55 adapted to be moved into line with the primary coil and complete the magnetic circuit of the primary coil, and a second magnetic member arranged to move with the secondary coil adapted to complete the magnetic 60 circuit of the primary coil outside of the secondary coil.

In witness whereof I have hereunto set my hand this 24th day of July, 1906.

EDWARD F. GEHRKENS.
